Primary Examiner — Cathron Brooks(74) *Attorney, Agent, or Firm* — Kenneth L. Green;
Averill & Green(57) **CLAIM**

The ornamental design for a bed frame, as shown and described.

DESCRIPTION

FIG. 1 is a perspective view showing the top, left side and front of the bed frame showing my new design.

FIG. 2 is a left side thereof, the right side view being the mirror image thereof.

FIG. 3 is a rear view thereof.

FIG. 4 is a front view thereof.

FIG. 5 is a perspective view showing the bottom, right side and thereof.

FIG. 6 is a top view thereof; and,

FIG. 7 is a bottom view thereof.

The broken lines in the drawings depict environmental matter only and form no part of the claimed design.

1 Claim, 2 Drawing Sheets(56)
